UNITED STATES PATENT OFFICE.

WILLIAM V. R. SELTZER, OF PHILADELPHIA, PENNSYLVANIA.

COIN-OPERATED STAMP-VENDING MACHINE.

No. 904,094.

Specification of Letters Patent.

Patented Nov. 17, 1908.

Application filed March 3, 1908. Serial No. 418,919.

To all whom it may concern:

Be it known that I, WILLIAM V. R. SELTZER, a citizen of the United States, residing at Philadelphia, in the county of Philadelphia and State of Pennsylvania, have invented 5 certain new and useful Improvements in Coin-Operated Stamp-Vending Machines, of which the following is a specification.

This invention relates to stamp vending machines, and more particularly to coin operated machines, the object being to provide a machine by means of which a stamp can be brought into view by the insertion of a coin, so that it can be readily removed.

10 Another object of my invention is to provide a machine which is composed of a very few parts which are so arranged that it is almost impossible to defraud the machine, and one which is exceedingly simple and 15 cheap in construction.

Another object of my invention is to provide very novel means for releasing the roller carrying the tape of stamps by the insertion of a coin, whereby the tape carrying 20 the stamps will be moved over an opening in the casing of the machine, so that the stamp can be readily detached from the tape by the purchaser.

Another object of my invention is to provide 25 a machine which will vend either one or two cent stamps.

A further object of my invention is to provide very novel means for releasing the roller carrying the tape of stamps.

30 These objects are obtained by the novel arrangement and construction of parts hereinafter fully described and shown in the accompanying drawings, in which:

Figure 1, is a perspective view of my improved machine showing the stamp brought into alinement with the opening ready to be removed. Fig. 2, is a vertical section through the same. Fig. 3, is a vertical section through the same taken from the other 45 side. Fig. 4, is a section taken on line 4-4 of Fig. 2. Fig. 5, is a top plan view, the casing being shown in section. Fig. 6, is a detail perspective view of the coin chutes and operating shaft detached, and, Fig. 7, is a 50 detail perspective view of the stamp carrying tape.

In the drawings A, indicates a base on which is mounted a casing B, having a hinged door B', an opening B², and spaced 55 slots B³, to the inner side of which are secured coin chutes C, provided with offset

portions C', in which are mounted the vertical ends D', of a U-shape frame D, adapted to be operated by an arm E', carried by a shaft E, which extends out through the casing between the slots, and is provided with a knob E², by means of which it is turned, the vertical portion D', being surrounded by coil springs E³, for returning the frame to its normal position after it has been compressed by the arm E', as will be hereinafter 60 fully described.

Arranged within the casing is a frame F, between the horizontal members of which are mounted shafts G and H, carrying 70 grooved rollers G', H', having gear wheels G², H², secured thereto, which mesh with each other, whereby when the roller G', is turned in one direction, the roller H', will be turned in a reverse direction, and mounted 75 on the roller G', is a metal tape I, which passes over anti-frictional rollers I', arranged across the opening B², of the casing, and then around the roller H', so that as the tape is unwound from the roller G', it will 80 be wound upon the roller H', and to operate the rollers I secure on the shaft G, one end of a coil spring J, the other of which is secured to a casing J', secured to one of the gear wheels G².

85 Secured to the top of the frame is a bracket K, carrying pivoted locking levers L, provided with enlarged heads L', adapted to fit between the teeth of the gear wheels G², and be held therein by flat springs L², 90 carried by the bracket K, whereby the roller will be prevented from being rotated until the locking levers are thrown out of engagement with the gears, as will be hereinafter fully described. Secured to the ends of the 95 locking levers L, are rods M, which are provided with angle ends having enlarged portions M', adapted to be normally held up against the bottom of the coin chute C, and it will be seen that when a coin is inserted 100 through the slots into each of the coin chutes and the knob is turned, the depending ends D', will be brought against the coin, so as to force the rods M, downwardly, which will throw the locking levers out of engagement 105 with the gears G². The metal tape I, is provided with lips I², which are punched out of the same, under which stamps are adapted to be inserted, so that when brought into alinement with the opening B², they can be readily removed from the same.

110 A chute N, provided with an enlarged

mouth is arranged under the coin chutes and extends down over a drawer O, arranged in the bottom of the casing in which the coins are deposited, the drawer being provided 5 with a suitable lock.

The operation of the device is as follows: When it is desired to purchase a stamp, if two cent stamps are arranged on the tape, a penny is inserted in each of the slots, so that 10 it will drop into the coin chute onto the enlarged ends M', of the rods M, and as the knob E², is turned, the arm E', will be brought into engagement with the frame D, so as to force the depending ends down 15 against the coin, which will draw the rods downwardly and release the locking levers, so that the roller G, will be rotated by the spring, which will bring the stamp on the tape over the opening so that it can be readily 20 removed.

It will be seen that as the coins are forced down by the frame D, when they pass out of the chutes they will drop off of the enlarged ends of the rods M, which release the locking 25 levers, so that they will drop back into the gears, so as to prevent the tape from unwinding only a certain distance which is only enough to bring one stamp into the opening, so that it can be readily removed.

30 When one cent stamps are arranged on the tape, it is only necessary to insert a penny in one of the slots which will depress the rod and release the lever, it of course being understood that one of the locking levers is to 35 be removed.

From the foregoing description it will be seen that I have provided a stamp vending-machine which is so constructed that the stamps will be kept in good condition, as the 40 tape can be coated with wax or some other suitable material so as to prevent the stamps from sticking to the same in warm weather.

Having thus described my invention what I claim as new and desire to secure by Letters 45 Patent is:—

1. A stamp vending machine comprising a casing, a pair of rollers mounted in said casing, a tape passing from one roller to the other roller across an opening in the said 50 casing, said tape being adapted to hold a series of postage stamps, a spring on one roller acting to unreel the stamp carrying tape, independent locks for locking one of said rollers against the action of the spring, in- 55 dependent levers for actuating said locks and a single depression bar adapted to engage with one or the other, or both of said locking levers, and means for actuating said depression bar.

60 2. In a stamp vending machine, a pair of rollers, a tape passing from one roller to the other roller and holding a series of stamps, means for unwinding said tape from one roller, and two independent locking devices

holding the roller from actuation by said 65 spring, and a single operating means adapted to actuate one or the other, or both of said locking levers.

3. In a vending machine, rollers, a delivery tape passing from said roller to the other, means acting to unwind the tape from one roller and wind it upon the other, locking devices engaging with one of said rollers and independent of each other, rods connected to said locking devices and having enlarged ends, chutes the lower ends of which are covered by said enlarged ends of the rods, connected depression bars entering said chutes but not contacting with the enlarged ends of the bars, and means for actuating 75 said depression bars both at the same time.

4. A stamp vending machine comprising an oblong casing having a stamp opening in its end, upper and lower rollers mounted in 85 the sides of said casing and engaging with each other, a stamp carrying tape carried by said rollers, anti-friction rollers located on opposite sides of the stamp opening over which said stamp tape passes, a spring 90 adapted to unwind the tape from one roller and winding it upon the other, locking levers pivoted in the upper portion of said casing independent of each other and engaging with one of said rollers to hold it from movement, 95 independent rods connected to each of said locking levers and extending downward, said rod having inwardly turned ends provided with enlarged heads, independent chutes normally closed at their lower ends by said enlarged heads, connected depression bars entering 100 said chutes and having movement therein, and means for moving the depression bars as one.

5. In a stamp vending machine, a casing, 105 opposed rollers mounted in the casing and intermeshing with each other, a stamp carrying tape mounted on said rollers adapted to be unreeled from one and be reeled up on the other, a locking lever normally engaging the gear teeth of the upper roller to prevent its actuation, rods depending from said locking lever having inwardly turned ends, a spring, a U-shaped bar the ends of which engage with the inturned ends of said 110 rolls, and a rotatable shaft projecting through the side of the casing and having an arm adapted to engage with said U-shaped 115 bar to depress the same to raise said locking lever out of engagement with said upper 120 roller.

In testimony whereof I have signed my name to this specification in the presence of two subscribing witnesses.

WILLIAM V. R. SELTZER,
Witnesses.
